UNITED STATES PATENT OFFICE.

JOSEPH ADIE WHITE, OF CHICAGO, ILLINOIS, ASSIGNOR TO F. S. WEBSTER COMPANY, OF BOSTON, MASSACHUSETTS, A CORPORATION OF MASSACHUSETTS.

CARBON BINDER AND ECONOMIZER.

1,391,872.

Specification of Letters Patent. Patented Sept. 27, 1921.

Application filed February 13, 1920. Serial No. 358,463.

To all whom it may concern:

Be it known that I, JOSEPH A. WHITE, a citizen of the United States, residing at Chicago, in the county of Cook and State of Illinois, have invented an Improvement in Carbon Binders and Economizers, of which the following is a specification.

This invention relates to a method of type-writing duplicates and to means for lengthening the life of or economizing the fragile carbon sheets employed in preparing duplicates.

In this specification I refer to the sheet nearest the type, which receives the impression from the ribbon as the original sheet. According to the present practice, by which the first carbon sheet is next to the original sheet, the carbon sheet rapidly deteriorates and ordinarily will make but relatively few duplicates before being worn out by the blows of the type. By the use of my invention, however, I am able to increase the working life of the carbon sheets to an extraordinary degree, so that with the use of high grade carbon paper I can obtain more than one hundred impressions, whereas without the use of my invention, even with the best of paper, it is difficult to obtain as high as thirty impressions.

My invention comprises placing a protective sheet between the original sheet and the first carbon sheet.

The protective sheet may be of any suitable material and Japan vellum paper, and light tracing cloth have been found to be very effective in greatly extending the life of the carbon sheets.

The protective sheet must not be so heavy as to prevent the necessary clearness of the impressions made by the carbon sheets, and must therefore, suitably transmit the blows of the type and yet be sufficiently tough to withstand the blows and cutting action of and be impenetrable to the type until the carbon paper has been used to the designed extent. The Japan vellum paper and light weight tracing cloth above referred to are admirably suited for the purpose.

I assemble the protective sheet and carbon sheets in a unitary pack which I term a carbon binder and economizer in which the several sheets are adapted to receive between them the sheets on which the impressions are recorded, with the protective sheet

interposed between the original and the first 55 carbon sheet.

In building up such a pack I find it desirable to arrange a backing sheet upon which I place the desired number of carbon sheets with their impression faces downward. On 60 top of the carbon sheets I place the protective sheet. The backing sheet is then folded over the carbon sheets and the protective sheet and the entire pack is stitched or otherwise fastened at the top preferably for its 65 entire length.

In use the sheets to receive the impressions are placed between the carbon sheets in the usual manner and the original sheet is placed over the protective sheet and tucked under 70 the flap of the backing sheet, and the entire pack is placed in the typewriting machine in the normal manner.

My invention is particularly valuable when used in connection with the carbon 75 binder and economizer for the reason that it is difficult otherwise to use the carbon sheets enough times to get the full benefit of my invention, because of the wrinkling and tearing of the carbon sheets by handling them 80 many times. The carbon binder and economizer holds the sheets in their proper place and avoids the necessity for repeated handling thereof, and protects them against injury.

Figure 1 is a view of a carbon binder and economizer embodying my invention.

Fig. 2 is a view of a carbon binder and economizer embodying my invention especially adapted for billing.

Fig. 3 is a detail illustrating the relative arrangement of the protective sheet and carbon sheets when the binder is filled for use.

Fig. 4 is a longitudinal sectional elevation of the binder and economizer of Fig. 1.

As here shown my invention is associated with the carbon binder and economizer having the backing sheet 10 of any suitable material and dimensions. A plurality of carbon sheets 11 are received on the backing 100 sheet with their impression faces downward and on top of the carbon sheet is placed the protective sheet 12. The top edge of the backing sheet is turned over the top edges of the protective and carbon sheets and the 105 entire pack is secured together at the top by stitching 13. The reflexed end of the backing sheet extends over the protective sheet

below the line of stitches to provide a flap 14 between which and the protective sheet, the original paper sheet is adapted to be received and retained for typewriting.

5 My invention is especially valuable for the work of billing and in Fig. 2, I have illustrated a binder and economizer with my protective sheet embodied therein especially adapted for this work. The backing 10 sheet, the protective sheets and the carbon sheets are arranged as usual but some of the carbon sheets may be incomplete, that is, they may not extend the entire width of the binder and economizer. The first carbon 15 sheet, for instance, while extending the entire width of the device, is longitudinally slit to form in effect three carbon sheets as 11^a, 11^b, and 11^c. The second carbon sheet 11^d extends from one edge only about 20 to the middle of the binder, and other carbon sheets extend in from one edge to an even less distance. By this arrangement 25 certain of the duplicate or impression sheets may have certain data, as columns of numbers, omitted while such data may appear on other duplicate sheets.

Fig. 3 clearly illustrates the manner of using the binder and economizer embodying my invention. The duplication or impression sheets *a* are alternately disposed with the carbon sheets 11 and the original sheet *b* is tucked under the flap 14 over the protective sheet 12.

The binder with sheets assembled therein 35 is placed in the typewriting machine and the typing operation is carried out in the usual manner.

The bottom edges of the backing sheet, and the protective sheet and the carbon 40 sheets may have alined notches or thumb spaces 16 therein, as shown in Fig. 1 whereby

the original and duplicates may all be grasped between the thumb and a finger without also grasping the carbon sheets, for removal from the binder.

I claim:

1. A carbon binder comprising a sheet of carbon paper and a superposed separate sheet of vellum which protects the carbon sheet from being cut by the type, both fastened together at their top edges.

2. A carbon binder comprising a sheet of backing paper and a sheet of vellum which protects the carbon paper from being cut by the type, the backing sheet and vellum sheet having stitched between them a sheet or sheets of carbon paper.

3. A carbon binder comprising a sheet of carbon paper and a superposed, separate type-impenetrable, type-blow-transmitting sheet, which protects the carbon sheet from being cut by the type, both fastened together at their top edges.

4. A carbon binder comprising a backing sheet, one or more sheets of carbon paper, and a top type-impenetrable, type-blow transmitting sheet which protects the carbon paper from cutting by the type, all united at their top edges in the order named.

5. A carbon binder comprising a backing sheet and a sheet of type-resisting material which protects the carbon paper from being cut by the type, said backing sheet and protective sheet having stitched between them a sheet or sheets of carbon paper.

In testimony whereof, I have signed my name to this specification, in the presence of two subscribing witnesses.

JOSEPH ADIE WHITE.
